UNITED STATES PATENT OFFICE

HERBERT S. MILLS, OF OAK PARK, ILLINOIS, ASSIGNOR TO MILLS NOVELTY COMPANY, OF CHICAGO, ILLINOIS, A CORPORATION OF ILLINOIS

ROSIN-APPLYING DEVICE

Application filed July 9, 1925. Serial No. 42,459.

The present invention relates particularly to an automatically actuated rosin-applying device adapted for use in connection with electrically operated machines employing 5 stringed instruments of the viol class.

A machine of the general type referred to is disclosed in Sandell's Letters Patent of the United States 855,021, granted May 28, 1907.

In such a machine, rotating bows, usually 10 comprising celluloid disks, are depressed, or brought into contact with the strings, at proper times, suitable fingering devices being employed to enable the selected note to be sounded. In the type of machine referred to, 15 the actuation of the fingering devices, the rotation of the bows, and the depression of the bows into contact with the strings are effected by suitable electric apparatus.

The present invention is more particularly 20 applicable to machines of the class referred to which employ a note-sheet for controlling the electric circuits which function in the playing of the instrument. In machines of the type just referred to, the note-sheet passes 25 from a music roll over a tracker-bar, or its equivalent, with which cooperate a series of contacts associated with the electric circuits which control the fingering and the depression of the bows. Similarly controlled electric 30 circuits for expression purposes are commonly employed. For the purpose of the present invention, it is unnecessary to show and describe the contacts and circuits mentioned.

In machines of the kind here referred to, 35 the music sheet is stored on a roll, usually termed the music roll, and passes therefrom about a metallic roll, or tracker-bar, and thence to a take-up roll. After the music has 40 been played, it is necessary to rewind the music sheet upon the music roll. Mechanism for actuating the rolls to feed the music sheet during the playing operation and then effect rewinding of the music sheet upon the music 45 roll is well known in the art. Mechanism of this character is disclosed, for example, in Sandell's United States Patent 1,302,439, granted April 29, 1919.

The present invention makes use of the feature of an electromagnetic device for apply-

ing the rosin to the bows during the period when the rewinding of the music sheet from the take-up roll onto the music roll occurs. The circuit of the electromagnetic device is controlled by means of a member which 55 presses against the portion of the music sheet which is upon the take-up roll; and preferably, the arrangement is such that this member operates to close the circuit of the electromagnetic device and maintain it closed during a period which corresponds approximately with the final portion of the transfer of the music sheet from the take-up roll to the music roll.

The invention is illustrated in its preferred 60 embodiment in the accompanying drawing, in which—

Fig. 1 represents, diagrammatically, a 65 broken vertical sectional view of a portion of a music machine of the kind mentioned, the view showing the take-up roll, a portion of the music roll, and the rosin-applying device; and Fig. 2 represents a broken plan view of the switch device which appears at the lower 70 left hand portion of Fig. 1.

In the illustration given, A designates a 75 rotary bow carried by a shaft A' which is capable of depression to bring the bow into contact with the string (not shown); B designates a music roll on which the music sheet 80 normally is stored; C designates the take-up roll; D designates the music sheet; E designates the tracker-bar, or roll, over which the music sheet passes, this member co-acting 85 with the series of circuit-controlling contacts (not shown) in the usual manner; and F designates the rosin-applying device whose movements are controlled by the electromagnetic device F'.

During the playing operation, the take-up 90 roll C rotates in the direction indicated by the arrow, and after the music has been played, the reversible sheet-feeding mechanism operates to turn the music roll B in a direction to rewind the music sheet upon 95 the music roll. This may be accomplished, for example, by means of the reversible sheet-feeding mechanism described in the second-mentioned patent.

The device F comprises preferably an in- 100

verted box-like rosin-holder 1 which contains blocks, or masses, of rosin, 1^a, adapted to bear against the bows when the device 1 is in the depressed position shown. The box, or holder, 1 has an arm 1^b which is mounted on a stationary pivot 2. Rigidly connected with the arm 1^b is an arm 3 which serves as an armature for an electromagnet 4 which constitutes a part of the electromagnetic device 10 F'. The solenoid of the magnet 4 is provided with a circuit 5 which may be energized from any suitable electric source (not shown). Interposed in the circuit 5 is a switch device 6, which, in the illustration given, comprises a lever 6^a, a contact-member 6^b pivotally mounted on said lever, and a co-acting contact-plate 7 with which one line of the circuit connects.

The contact plate 7 is shown adjustably mounted upon a stationary block 8, and adjustably associated with the plate 7 is an insulation member, or insulated member, 9, which serves as a rest, or detaining member, which arrests the contact-member 6^b in its downward course, but which finally allows said contact-member to snap off and come quickly into contact with the contact-plate 7. The plate 9 is mounted on insulation washers 10 which are supported on the contact-plate 7. Screws 11 secure both plates and the interposed washers to the supporting base 8. Both the plates 7 and 9 preferably are provided with slots which permit them to be adjusted toward or away from the pivotally mounted contact-member 6^b.

35 The lever 6^a is shown in the form of a bell-crank lever having its central portion mounted on a stationary pivot 12. One arm of the lever is equipped with a roller 13 adapted to bear on the portion of the music sheet which is wound on the take-up roll C. The other arm of the lever 6^a carries the pivotally mounted contact-member 6^b, which is pivotally mounted on a stud 14. The member 6^b has an arm which extends back of the pivot 14 and which is connected by a light coil-spring 15 with a stud 16 which projects laterally from the lever 6^a. Rigidly attached to the contact-member 6^b is a cam-like insulation piece 17 which projects sufficiently past the upper edge of the free extremity of the contact-member 6^b to prevent engagement with the contact-plate 7 on the up stroke of the arm which carries the member 6^b.

55 A spring 18 attached to a stationary member 19 serves to maintain the lever 6^a in such position that the roller 13 will always bear against the music sheet on the take-up roll C.

A spring 20 attached to a stationary support 21 tends to lift the rosin-holder 1 to a position where it bears against a stop 22, in which position the rosin device will be free from contact with the rotating bows of the instrument.

60 The lever 6^a is shown equipped with a spring-held pivotally mounted contact-mem-

ber 23 which co-acts with a contact-plate 24. The members just referred to form no part of the present invention, but may be employed for other purposes. It may, for example, serve in connection with the reversal of the sheet-feeding mechanism to set the same in condition for a subsequent playing operation.

65 From the description given, the operation of the improved device herein illustrated will be readily understood. During the playing operation, the music sheet is wound upon the take-up roll C. As the roll of the music sheet enlarges on the take-up roll, the roller 13 is depressed and thus moves the arm carrying the contact-member 6^b upwardly to a position well above the insulated plate 9. During this movement, the contact-member 6^b cannot come into contact with the contact-plate 7 because the insulation piece 17 prevents such action. After the playing operation has been completed, the rewinding of the music sheet upon the music roll B takes place automatically in the usual manner. During the rewinding operation the arm carrying the contact-member 6^b descends constantly. The tendency of the contact-member 6^b to come into contact with the contact-plate 7 is overcome by the rest-plate 9, and as the arm continues its downward movement, the spring 15 is placed under increased tension. Finally, the contact-member snaps off the plate 9 and rests on the contact-plate 7, thus closing the circuit of the electromagnet 4. When this occurs, the arm 3 is drawn to the electromagnet, and the rosin-holder 1 is depressed so that the rosin blocks are brought into contact with the rotating bows, of which the usual number, four, are illustrated in the drawing. The rosinning action continues until the contact-member 6^b snaps off the contact-plate 7. This breaks the circuit of the electromagnet 4, and the spring 20 operates to lift the rosiner away from the bows.

70 It is preferred to so arrange the device that the rosinning action will occur during about the final one-third, or one-fourth, portion of the rewinding operation. However, the plates 7 and 9 may be adjusted to control the length of time of the application of the rosin to the bows. The longer the contact-member 6^b remains in contact with the contact-plate 7, the longer will be the period of the rosin-applying operation. Obviously, the plates 70 may be adjusted to control this period. Moreover, the apparatus may be designed to cause the rosin to be applied during any desired portion of the rewinding operation.

75 The foregoing detailed description has been given for clearness of understanding only, and no unnecessary limitations should be understood therefrom.

80 What I regard as new, and desire to secure by Letters Patent, is:

85 In a musical instrument of the viol class,

a device for applying rosin to the bows comprising a pivotally mounted rosin-holder equipped with an armature, a solenoid adapted to move said armature in such direction as to move the rosin-applying device into contact with the bows and circuit-controlling means for said solenoid comprising a contact-plate and an associated insulation plate provided with means for permitting adjustment relative to said contact plate, a pivotally mounted lever having an arm equipped with means adapted to co-act with the music sheet on a take-up roll, and a spring-held pivotally mounted contact-member carried by said lever and equipped with an insulation piece adapted to prevent closing of the circuit in one direction of movement of said lever, said pivotally mounted contact-member being adapted to be arrested by said insulation plate during the other direction of movement of said lever and then snap into contact with said contact-plate.

HERBERT S. MILLS.
